L. E. ZERBE

BUSHING RETAINER FOR ROTARY DRILL TABLES

Filed Feb. 20, 1922

Inventor
Lewis E. Zerbe.

By Lyout & Lyout attys

UNITED STATES PATENT OFFICE.

LEWIS E. ZERBE, OF MONETA, CALIFORNIA, ASSIGNOR TO UNION TOOL COMPANY, OF TORRANCE, CALIFORNIA, A CORPORATION OF CALIFORNIA.

BUSHING RETAINER FOR ROTARY-DRILL TABLES.

Application filed February 20, 1922. Serial No. 538,059.

To all whom it may concern:

Be it known that I, LEWIS E. ZERBE, a citizen of the United States, residing at Moneta, in the county of Los Angeles and 5 State of California, have invented a new and useful Bushing Retainer for Rotary-Drill Tables, of which the following is a specification.

This invention relates to a bushing retainer for rotary drill tables and has for an 10 object to provide a means preventing a vertical displacement of the bushings.

Another object is to provide a means for preventing a vertical displacement of the 15 drill-stem bushings and table bushings during an upward translation of the drill stem.

Another object is to provide a means which will prevent the bushings becoming 20 displaced through a chattering of the bushings during a drilling operation.

A further object is to provide a device 25 for preventing vertical displacement of the table bushings during a pipe pulling operation, without interfering with a free manipulation of the pipe slips.

Various other objects and advantages will 30 be more fully apparent from the following description and the accompanying drawings which form a part of this disclosure, 35 and which illustrate a preferred form of embodiment of the invention.

Of the drawings:

Fig. 1 is a perspective view of a rotary 35 drill table with my bushing retainer applied thereto.

Fig. 2 is a plan view, partly in section.

Fig. 3 is a section on line 3—3 of Fig. 2.

Fig. 4 is an elevation of the retaining plate, looking at its side edge.

In the drawings, 1 designates the rotary 40 drill table which may be of any well known or standard design, said table having the usual central throat opening 2 formed to receive the split table bushings 3 which are 45 formed with squared flanges countersunk into the table surface to prevent their turning in the throat.

Engaging within the table bushings 3 are 50 split drill-stem bushings 4 having squared flanges countersunk into the surface of the table bushings 3, the bushings 4 forming a square bore in which the drill-stem (not shown) engages.

The above general type of construction is 55 now so well known in the art that further

detailed description thereof is herein unnecessary, it being sufficient for the purpose of the present disclosure to state that in a drilling operation with the drill stem positioned within the bore of the bushings 4, a 60 rotation of the table will rotate the drill stem while at the same time permit a vertical translation thereof.

In withdrawing the drill stem from the well bore, the drill stem bushings 4 are removed and when desired to withdraw the drill pipe suitable pipe slips are employed in conjunction with the table bushings in the usual manner.

It has been found that in a drilling operation a chattering of the drill stem will likewise cause a chattering of the drill-stem bushings with the result that they have a tendency of creeping upwardly until their squared flanges are entirely free of the 70 table bushings, and in such instance their driving function is interrupted and they become so displaced as to cause serious damage to the equipment.

To prevent such displacement of the drill 75 stem bushings and to further prevent upward movement of both the drill-stem bushings and table bushings at any time while in use, or to prevent an upward movement of only the table bushings when the drill-stem bushings are not being employed, as 80 for instance in a pipe drawing operation, I have provided means for preventing upward movement of the bushings until such means is first withdrawn from the path of 85 withdrawal of the bushings.

Such means comprises a keeper which 90 may be in the form of a retaining plate 5 of approximate U-shape and I provide guiding means for the keeper receiving its opposed 95 limbs 6 slidably in slideways formed by opposed brackets 7 secured by bolts 8 to the surface of the table 1 upon opposite sides of the table throat opening 2. The plate 5 is provided with stop abutments 9 adapted to engage the respective brackets 7 to limit the inward movement of the plate 5 and as 100 a means for locking the plate in its inner position I provide lock studs 10 each engaging through relatively aligned apertures 11 in the respective brackets 7 and apertures 12 in the table surface and passing through a recess 13 in the respective edge of the plate.

The plate is provided with a handle 14 to 110

facilitate its manipulation and its central opening is so proportioned and contoured that when the plate is in inner position as shown in Figs. 1 and 2, it not only overlaps the table bushings 3 but also will overlap the outer corners of the drill-stem bushings 4 when such bushings are in use.

This construction provides a horizontally 10 slidable retaining plate or slide adapted to be moved to a position overlapping the table bushings to prevent their removal or displacement and which is locked in such position until released for subsequent removal from above the bushings to permit a removal of the bushings.

While the form of device herein illustrated and described is well adapted for the purposes primarily stated, it is to be understood that I do not wish to confine the invention to the one form of embodiment herein disclosed, for it is susceptible of embodiment in various other forms all coming within the scope of the claims which follow.

I claim:

- 25 1. In a device of the nature disclosed, the combination of a rotary drill table having vertically removable bushings, movable keeper means, and means for guiding the same into a position to prevent a removal 30 of the bushings.
2. In a device of the nature disclosed, the combination of a rotary drill table having vertically removable bushings, slideways on opposite sides of said bushings, and a retaining member engaging said slideways and movable to a position to overlap the bushings and prevent their removal.
3. In a device of the nature disclosed, the combination of a rotary drill table having vertically removable bushings, and means movable to a position to prevent a removal 40 of the bushings, and means locking the retaining member against withdrawal.
4. In a device of the nature disclosed, the combination of a rotary drill table having vertically removable bushings, horizontal slideways on opposite sides of said bushings, a retaining slide engaging said slideways and movable to a position to overlap 50 the bushings and prevent their removal,

means limiting the inward movement of said slide, and means locking the slide in its inner position.

5. In a device of the nature disclosed, the combination of a rotary drill table having a central throat, table bushings engaging within said throat, drill-stem bushings engaging within the table bushings, horizontal slideways on the table, and a retaining plate slidable in said slideways to a position to overlap the bushings and prevent their removal.

6. In a device of the kind described, the combination of a rotary drill table with a central opening, table bushings received in said opening and having flanges supported on the table, drill stem bushings received in the opening of the table bushings and having flanges resting on the table bushings and supporting the drill stem bushings, and removable means attached to the table for engaging the drill stem bushings to prevent their upward displacement, the drill stem bushings operating to prevent vertical displacement of the table bushings.

7. In a device of the kind described, the combination of a rotary drill table having a central opening, a split table bushing composed of two table bushing sections received in the said opening, a split drill stem bushing composed of two bushing sections received in the opening of the table bushings, said table bushings having flanges countersunk into the upper face of the table so that their upper faces are flush therewith and said drill stem bushings having flanges countersunk into the upper faces of the table bushing and flush therewith, and movable means for engaging the upper face of the drill stem bushings for holding the same against vertical displacement, said drill stem bushings operating to hold the table bushings against displacement.

Signed at Torrance, California, this 10th day of February, 1922.

LEWIS E. ZERBE.
